UNITED STATES PATENT OFFICE

151,429

DESIGN FOR AN ADJUSTABLE VISE-JAW
HOLDER AND SUPPORT THEREFOR

Herman E. Clauss, Afton, Mo.

Application March 1, 1946, Serial No. 127,001

Term of patent 7 years

(Cl. D54—13)

To all whom it may concern:

Be it known that I, Herman E. Clauss, a citizen of the United States, residing at Afton, in the county of St. Louis and State of Missouri, have invented a certain new, original, and ornamental Design for an Adjustable Vise-Jaw Holder and Support Therefor, reference being had to the accompanying drawing, forming part thereof.

Fig. 1 is a top plan view of an adjustable vise-jaw holder and support therefor, showing my new design.

Fig. 2 is a front elevation of the adjustable vise-jaw holder and support therefor, the jaw shown in broken lines being omitted for convenience of illustration.

Fig. 3 is a left hand end elevation of the adjustable vise-jaw holder and support therefor.

The essential features of my design are shown in full lines.

I claim:

The ornamental design for an adjustable vise-jaw holder and support therefor, as shown and described.

HERMAN E. CLAUSS.
